UNITED STATES PATENT OFFICE.

ROBERT CARR WALL, OF PHILADELPHIA, PENNSYLVANIA.

TIRE-FASTENING DEVICE.

1,087,618.

Specification of Letters Patent. Patented Feb. 17, 1914.

Application filed September 15, 1911. Serial No. 649,515.

To all whom it may concern:

Be it known that I, ROBERT CARR WALL, of Philadelphia, in the State of Pennsylvania, have invented a certain new and useful Improvement in Tire-Fastening Devices, whereof the following is a specification, reference being had to the accompanying drawing.

My invention relates to means for fastening pneumatic tires upon vehicle wheel rims and particularly to a divided retaining ring flange and means for securing it upon a wheel rim.

As hereinafter described, my invention includes a divided ring flange having inwardly projecting wedges at its ends, and wrench holds at its inner circumference near said ends, fitted to a rim having a slot to receive said wedges and fulcrum sockets affording access to said wrench holds; a lever wrench adapted to fit in said fulcrum sockets in engagement with said wrench holds, whereby said ring may be constricted upon said rim; and, means normally retaining said ring on said rim.

My invention includes the various novel features of construction and arrangement hereinafter more definitely specified.

In the drawing:—Figure I is a side elevation of a wheel felly, rim and retaining ring conveniently embodying my improvement. Fig. II is a sectional view taken on the line II, II, in Fig. I. Fig. III is a fragmentary side elevation of a wheel rim and retaining ring embodying a modified form of my invention. Fig. IV is a sectional view taken on the line IV, IV in Fig. III.

In the form of my invention shown in Figs. I and II; the metal rim 1 is fitted in concentric relation upon the wooden felly 2 to which it is conveniently secured by the screws 3. Said rim is provided with the removable ring flange 5 which is divided as indicated at 6 in Fig. I and has inwardly projecting wedges 7 at its ends extending in a plane transversely to its axis, with complementary recesses 8 in the contiguous edges of said wedges; wrench holds 10, ad- joining said ends, and conveniently oppositely inclined ratchets at the inner circumference of said ring. Said ring has the stud 11 projecting radially inward intermediate of its ends and fitted to the socket 12 in said rim 1, the latter having a slot 14 to receive said wedges 7, and fulcrum sockets 15

affording access to said ratchets 10. The screw 17 which extends in said recesses 8 normally retains said ring on said rim by engagement with said felly as indicated in Fig. II. Upon removing said screw 17 the ring 5 may be detached from the rim 1 by springing its ends outwardly with the lever 18 which may be conveniently engaged in the notches 20 in said rim. To replace said ring its stud 11 may be engaged with the socket 12 in said rim 1 and its ends sprung apart with the wedges 7 in alinement with said slot 14. Thereupon, the ring ends may be alternately shifted circumferentially to constrict said ring 5 upon the rim 1 and seat said wedges in said slot, by engagement of said lever 18 with the ratchets 10 through the fulcrum sockets 15. It may be observed that when the ends of said ring 5 are shifted circumferentially as above described and the wedges 7 pressed radially inward to the position shown in Fig. I, said wedges respectively bear upon the opposite ends of said slot 14 in the rim and thus prevent retraction of the ring from its constricted position to which it has been shifted by the lever 18; the angle of said wedges in contact with said rim being such that it is necessary to move them radially outward to release them. However, the screw 17 prevents their accidental displacement.

In the form of my invention shown in Figs. III and IV, the metal rim 21 is provided with the removable ring flange 22 which is divided as indicated at 23 in Fig. III and has inwardly projecting wedges 25 at its ends extending in a plane transversely to its axis, with complementary recesses or openings 26 in alinement in said wedges; the latter being fitted in the slot 27 in said rim 21 so as to present said openings within the latter as indicated in Fig. IV. Said ring 22 is normally retained on said rim by the cotter pin 28, one limb of which extends through said openings 26; the opposite end of said pin being bent as indicated at 30, forming a spring catch to engage the edge of the contiguous wedge 25 and prevent accidental removal of said cotter pin. Said rim 21 is not provided with notches to receive the lever 18 like the notches 20 shown in Fig. I; but, said ring 22 is provided with notches 31 to engage said lever whereby its ends may be sprung outwardly to remove it from said rim 21. Said ring 22 is also conveniently provided with wrench holds 32

similar to the wrench holds 10 in the ring 5, and, like the latter accessible for engagement with the lever 18 through fulcrum sockets 33 in said rim 21. Said ring 22 is 5 also conveniently provided with the stud 34 projecting radially inward intermediate of its ends and fitted to the socket 35 in said rim 21, which may be mounted upon a felly 36 as indicated in Fig. IV.

10 I do not desire to limit myself to the precise details of construction and arrangement herein set forth, as it is obvious that various modifications may be made therein without departing from the essential features of 15 my invention as defined in the appended claims.

I claim:—

1. A tire fastening device including a divided ring flange having inwardly projecting wedges at its ends extending in a plane transversely to its axis, with complementary openings in the contiguous edges of said wedges, oppositely inclined ratchets at the inner circumference of said ring adjoining its ends, and a stud on said ring projecting radially inward intermediate of its ends; a rim having a slot to receive said wedges, a socket for said stud, and fulcrum sockets affording access to said ratchets; a felly in 20 concentric relation with said rim within the latter; and, a cotter pin extending in said complementary openings, normally retaining said ring on said rim; said pin having means to resiliently engage said ring including an inwardly turned end overlapping the contiguous wedge.

2. A tire fastening device including a divided ring flange having inwardly projecting wedges at its ends extending in a plane 40 transversely to its axis, with oppositely inclined ratchets at the inner circumference of said ring adjoining its ends, and a stud on said ring projecting radially inward intermediate of its ends; a rim having a slot 45 to receive said wedges, a socket for said stud, and fulcrum sockets affording access to said ratchets; a felly in concentric relation with said rim within the latter; and, a cotter pin normally retaining said ring on 50 said rim by engagement with said wedges.

3. A tire fastening device including a divided ring flange having inwardly projecting wedges at its ends extending in a plane transversely to its axis, with oppositely inclined ratchets at the inner circumference of 55 said ring adjoining its ends, and a stud on said ring projecting radially inward intermediate of its ends; a rim having a slot to receive said wedges, a socket for said stud, and fulcrum sockets affording access to said 60

ratchets; and, means normally retaining said ring on said rim by engagement with said wedges.

4. A tire fastening device including a divided ring flange having inwardly projecting wedges at its ends extending in a plane transversely to its axis, with oppositely inclined ratchets at the inner circumference of said ring adjoining its ends, and a stud on said ring projecting radially inward intermediate of its ends; a rim having a slot to receive said wedges, a socket for said stud, and fulcrum sockets affording access to said ratchets; and, means normally retaining said ring on said rim. 75

5. A tire fastening device including a divided ring flange having inwardly projecting wedges at its ends extending in a plane transversely to its axis, with complementary openings in the contiguous edges of said 80 wedges, oppositely inclined ratchets at the inner circumference of said ring adjoining its ends; a rim having a slot to receive said wedges, and fulcrum sockets affording access to said ratchets; and, a cotter pin extending in said complementary openings, normally retaining said ring on said rim by engagement with said wedges. 85

6. A tire fastening device including a divided ring flange having inwardly projecting wedges at its ends extending in a plane transversely to its axis, with complementary openings in the contiguous edges of said wedges, and wrench holds at the inner circumference of said ring adjoining its ends; 90 a rim having a slot to receive said wedges, and fulcrum sockets in co-operative relation with said wrench holds; and removable means extending in said complementary openings, normally retaining said ring on 100 said rim by engagement with said wedges. 95

7. A tire fastening device including a divided ring flange having inwardly projecting wedges at its ends extending in a plane transversely to its axis, with oppositely inclined ratchets at the inner circumference of said ring adjoining its ends, and a stud on said ring projecting radially inward intermediate of its ends; a rim having a slot to receive said wedges, a socket for said stud; and, means normally retaining said ring on 105 said rim. 110

In testimony whereof, I have hereunto signed my name at Philadelphia, Pennsylvania, this fourteenth day of September, 1911.

ROBERT CARR WALL.
